FLEXIBLE SHAFT COUPLING

Lewis E. Baer, Hagerstown, Md., and Carroll G. Wright,
Fayetteville, Pa., assignors to T. B. Woods Sons Company,
Chambersburg, Pa.

Filed Nov. 8, 1974, Ser. No. 522,305

Term of patent 14 years

Int. Cl. D15—99

U.S. Cl. D55—1 G

FIG. 1

FIG. 2

FIG. 3

FIG. 1 is a perspective view of a flexible shaft coupling showing our design.

FIG. 2 is an end elevation thereof, the opposite end being identical to the end shown.

FIG. 3 is a top plan view thereof.

We claim:

The ornamental design for a flexible shaft coupling, as shown and described.
